UNITED STATES PATENT OFFICE.

CHESTER L. SHARP, OF LANCASTER, OHIO; GEORGIA SHARP ADMINISTRATRIX OF
SAID CHESTER L. SHARP, DECEASED.

GAS BURNER FOR FURNACES.

1,422,891.

Specification of Letters Patent.

Patented July 18, 1922.

Application filed June 10, 1921. Serial No. 476,629.

To all whom it may concern:

Be it known that I, CHESTER L. SHARP, a citizen of the United States, and a resident of Lancaster, in the county of Fairfield and 5 State of Ohio, have invented certain new and useful Improvements in Gas Burners for Furnaces; and I do hereby declare the following to be a full, clear, and exact description of the invention, such as will enable others skilled in the art to which it 10 appertains to make and use the same.

This invention relates to improvements in gas burners for furnaces and more particularly to such as are adapted for burning producer gas,—one object of the invention being 15 to so construct the valve construction for the burner as to prevent the accumulation of tar on the valve and its seat.

A further object is to provide a simple 20 burner construction which shall embody provision for effectually supplying air to support combustion; which shall be prevented from clogging at the valve; which can readily be kept clean; in which simple 25 means shall be provided to operate the valve, and which may also be utilized for burning oil or natural gas instead of producer gas.

With these and other objects in view, the 30 invention consists in certain novel features of construction and combinations of parts 35 as hereinafter set forth and pointed out in the claims.

In the accompanying drawings, Figure 1 35 is a sectional view of a burner embodying my improvements. Figure 2 is a rear view. Figure 3 is a detail view of the valve, and Figures 4 and 5 are views of modifications.

In the embodiment of my invention shown 40 in Figure 1, the body portion of the burner is indicated at 1 and provides a gas chamber 2 terminating in a nozzle 3, and a valve chamber 4. The burner is also provided with an air chamber 5 over the upper portion thereof and receives air from a suitable 45 source of supply through an inlet 6. It will be observed that the air chamber 5 is disposed over the gas chamber and said air chamber and a portion of the air inlet 6 are divided centrally by a partition 7 and that 50 said air chamber discharges air to be mixed with the nozzle portion of the burner.

The rear portion of the body of the burner 55 is provided with a vertical conduit 8 which provides a gas inlet 9 and this conduit is provided with a flange 10 seated in a suitable

receptacle 11 containing a sand seal 12. The conduit 8 and its union with the body of the burner is such as to provide an inclined valve seat 13 for an inclined valve 14 which controls the passage of gas into the burner. The 60 valve 14 may be inserted into the burner through an opening in a side wall thereof. The body of the burner will preferably be made in diametrically opposite walls with openings to facilitate the insertion or removal of the valve and these openings are normally closed by doors such as indicated at 15. At one end, the valve is provided with arms 16 projecting at an angle therefrom and seated against the end wall of the 70 burner in proximity to the lower portion of the inclined valve seat. The rear portion of the body of the burner is made with an opening 17, over which a plate 18 is secured,—said plate having an opening 19 so shaped 75 that its lower wall will form a tooth 20. A toothed bar 21 having a handle 22, passes through the opening 19 into the gas chamber and at its inner end, this toothed bar is provided with a hook to engage a pin 23 carried 80 by the valve 14. At suitable places in the wall of the burner adjacent to the rear portion of the gas chamber, holes 24 may be provided to permit the insertion of a cleaning 85 tool.

It is well known that producer gas coming 90 in contact with a valve or other part of a burner will leave a deposit of tar, an accumulation of which will tend to clog and seriously interfere with the efficient operation of the burner and its valve. By so arranging the valve and its seat that they will be disposed in an inclined position, as shown in the drawings, any tar which might become deposited on these parts will at once 95 run back into the producer gas tunnel. It will be observed that the burner is comparatively short and hence the rear portion thereof in which the valve is located will become highly heated and thus the ready 100 discharge of tar deposits will be facilitated. By mounting the inclined valve 14 in the manner above described, it will, when manipulated by the toothed bar to open it, be raised entirely from its seat and therefore all portions of the latter may be kept 105 clean from tar deposits.

In addition to tar, soot may accumulate at the valve and to cause the removal of this, the valve may be closed a few times sharply 110

against its seat to jar the soot loose and then the valve will be opened wide and the loosened soot will be blown into the furnace and escape through the stack.

5. If desired to employ oil or natural gas the valve 14 may be left closed, the operating bar and plate 18 removed and a suitable oil or natural gas injector located in position to discharge oil or natural gas through the 10 opening 17 into the burner.

Instead of locating the air chamber over the upper portion of the burner body, I may employ an air chamber extending completely around the forward portion of the 15 burner as indicated at 25 Figure 4. This air chamber is divided by a partition 26 and the rear portion of said chamber is spirally formed as at 27 and thus the air will be evenly distributed at the nozzle of the burner 20 and will be caused to make a swirl as it passes through the respective parts of the air chamber.

Instead of forming the air chamber over or around the body of the burner, I may 25 employ jet devices, such as shown at 28 Figure 5 entering the gas chamber in rear of the nozzle. In Figure 5 of the drawing I have shown a single air jet device 28 but it is evident that several of these may be employed.

Having fully described my invention what I claim as new and desire to secure by Letters-Patent, is:

1. In a gas burner of the type specified, 35 the combination of a body portion forming a gas chamber terminating at one end in a nozzle and provided at its other end with a gas inlet portion said body portion provided therein with a valve seat inclining downwardly toward the gas inlet, a valve to rest 40 on said seat, and means for manipulating said valve.

2. A gas burner of the type specified having a gas inlet portion formed with an inclined valve seat, an inclined valve to rest 45

on said seat, means for manipulating said valve, and arms projecting from said valve and engaging a portion of the burner body adjacent to the lower portion of the valve, whereby when the valve is raised it will 50 leave all portions of the seat.

3. In a burner of the type specified, the combination of a body portion having a gas inlet portion provided with an inclined valve seat, an inclined valve to rest on said seat, 55 said body portion having an opening, a plate over said opening having a hole formed to provide a tooth, and a manually operable ratchet bar passing through said hole and adapted to engage said tooth, said ratchet 60 bar being connected with said valve.

4. In a gas burner of the type specified, the combination of a body portion forming a gas chamber terminating at one end in a nozzle and provided at its other end with a gas inlet portion provided with an inclined air seat, a valve to rest on said seat, means for manipulating said valve, and means for discharging air toward the nozzle portion of the burner.

5. In a burner of the type specified, the combination of a body portion terminating at its forward end in a nozzle portion and provided at its rear end with a gas inlet portion having an inclined seat, an inclined valve to rest on said seat, means for manipulating said valve, an air chamber over the forward portion of said body portion and extending to the nozzle portion of the burner, an air inlet at the other end of said 75 air chamber, and a central partition dividing said air chamber and air inlet.

In testimony whereof, I have signed this specification in the presence of two subscribing witnesses.

CHESTER L. SHARP.
